PARKING METER HOUSING

Frank L. Michaels, Erlanger, Ky., assignor to The Michaels Art Bronze Company, Inc., Erlanger, Ky., a corporation of Kentucky

Filed Apr. 26, 1963, Ser. No. 74,639

Term of patent 14 years

(Cl. D52—3)

I claim:

The ornamental design for a parking meter housing, substantially as shown.
